CONTROL VALVES FOR HYDRAULIC TRANSMISSION SYSTEMS FOR WINCHES

Hans Hildre, Brattvaag, Norway, assignor to
Hydraulik A/S, Brattvaag, Norway

Filed Mar. 20, 1959, Ser. No. 800,817

3 Claims. (Cl. 121—46.4)

This invention relates to a control valve for hydraulic transmission systems and particularly to a control valve for hydraulic winches for use in the handling of cargo and baggage on board ships and for general use on board fishing boats, such as for hauling in fishing nets and the like.

Hydraulic transmission systems for which the control valve according to the present invention is primarily included are described in Patents 2,655,000; 2,718,759; 2,618,291; 2,749,709; 2,822,668; and 2,736,170.

In winches of the kind referred to it is desirable to have means for returning the control valve to its stop or neutral position automatically when the operator disengages his manual control handle. In this stop position, the winch drum is stopped and preferably positively locked against movement in at least the lowering direction.

It is an object of the present invention to provide a simple, reliable and advantageous return mechanism of the control handle and its associated valve member in such winches.

Another object of the present invention is to provide an arrangement wherein the return movement of the control handle proceeds smoothly and slowly in order to avoid shocks in the hoisting line due to sudden changes in the hydraulic system.

Accordingly, the invention consists of a manually operated control valve for hydraulic transmission systems, comprising a housing having a valve chamber, a supply conduit for pressure fluid from a fluid source to said valve chamber, a conduit for discharge fluid to said fluid source from said valve chamber, conduits for supplying and discharging hydraulic fluid to and from an hydraulic motor means from and to said valve chamber, all of said conduits opening into said valve chamber at spaced positions, a slide member displaceably mounted within said valve chamber, said slide member carrying flanges or lands for dividing the valve chamber into communication spaces for setting up desired flow paths for the hydraulic fluid from one conduit to another within said valve chamber, a manually operable control handle, said control handle being connected to said slide member whereby movement of said control handle to and from a central position into either of two opposite directions will move the slide member so as to shift the flow paths of said valve chamber, said central position representing a stop position whereas the movement into a respective one of said opposite directions will set up flow paths to drive the hydraulic motor means in a respective one of opposite directions, means for resiliently urging said control handle towards its central position, and means for dampening the return movement to said central position resulting from a manual displacement therefrom and subsequent release of said control handle.

Further objects, advantages and features of the invention will be apparent from the following description of one embodiment given by way of example, with reference to the accompanying drawings, in which:

Figure 1 is an axial sectional view of an embodiment of

2

a control valve according to the present invention, the valve member being shown in its intermediate or stop position.

Figure 2 is a wide view corresponding to the sectional view of Figure 1, showing the valve member in its hoisting position, or in the position of rotating the hydraulic motor in one direction.

Figure 3 is a view corresponding to the sectional views of Figures 1 and 2, showing the valve member in its position of positive lowering, or the position for rotating the hydraulic motor in the opposite direction.

Figure 4 is a simplified plan view of the valve housing.

Referring now to these drawings the control valve comprises a housing 10 enclosing a member 11 axially slidable within a cylindrical valve chamber 12 of said housing. The valve member is at its upper end provided with a lug 13 to which one end of a link 14 is pivoted, the other end of said link being pivoted to the outer end of a lever 15 the opposite end of which is keyed to a rotatable shaft 16 extending through packings (not shown) to the outside of said housing where an operating handle 17 is keyed to said shaft, whereby the axial position of the slide member within the valve chamber can be shifted by operation of said handle.

Pressure fluid is supplied to the housing from a pump, (not shown), through an auxiliary housing 18, from which channels extend to two openings 19 and 20 in the wall of valve chamber 12 at the central portion thereof with respect to the main axis of the valve chamber. A check valve 21 is arranged in said auxiliary housing, the function of which is described in the above mentioned Patent No. 2,736,170. In the axial direction of the valve chamber 12, the openings 19 and 20 are separated by a wall portion 22.

Discharge fluid is returned from the lower end of the valve chamber 12 through an opening 23 leading either to a sump or directly into the suction pipe of the pump. The upper end of the valve chamber is constantly connected to the discharge by an opening 24 communicating through a channel (not shown) in the wall of the housing with the lower end of the valve chamber.

At an axial position between the central openings 19, 20 and the upper end opening 24 a motor supply opening 25 is arranged. At an axial position between the said central openings 19, 20 and the lower end opening 23, a motor discharge opening is arranged.

The slide member 11 carries at its upper end two disc shaped plate members together forming an upper flange or "land" 27, at its central portion a number of disc shaped plates together forming a broad central flange or land 28, and a lower flange or land 29 at its lower end.

To the upper end cover 30 of the housing a downwardly extending rod 31 is secured, said rod carrying at its lower end a piston 32 arranged within an interior cylinder bore 33 of the slide member. Said cylinder bore 33 of the slide member is open at its lower end, whereas its upper end is closed by a plate member 34 forming an integral part of the upper flange. A first tubular sleeve 35 surrounds the rod 31 and extends upwards, the upper end of said sleeve 35 being spaced from the lower face of top cover 30 in the position of Figure 1. Furthermore, said sleeve is surrounded by a first compression spring 36 between the top cover 30 and the plate member 34.

A second compression spring 37 is arranged between the lower face of the plate member 34 and a spring supporting disc 38. A second tubular sleeve 39 is secured to or rests on said spring supporting member, said sleeve surrounding the rod and extending upwardly to terminate at a predetermined distance from the lower face of the plate member 34. In the stop or neutral position of the slide member, the spring supporting disc 38 rests on two

stops 40 preventing downwards movement of the disc 38, in said neutral or stop position the spring supporting disc further rests on a third tubular sleeve 41 surrounding the rod 31 and extending upwards from the piston 32 to the lower face of the spring supporting disc 38.

It should be noted that the three sleeves 35, 39 and 41 preferably only loosely surround the rod 31 so as to rest under their own weight on their respective supporting part, there being no necessity for said sleeves to be secured to such supporting parts.

Adjacent to the lower face of the broad intermediate flange or land 28, a narrow radial passage 42 extends from the periphery of said flange to the hollow interior of the slide member. Said passage is situated so that in the stop or neutral position its opening will be covered by the wall portion 22 between the central supply openings 19 and 20.

The upper plate member 34 is provided with another narrow passage 43 extending from the outside of the slide member into the hollow interior thereof.

It should also be noted that a locking member 44 having a fork-shaped construction as shown in Figure 4 is pivotally mounted for rotation about a horizontal pivot 45. By swinging said fork member downwards, the operating handle may be locked in the stop or neutral position to prevent it from being displaced inadvertently from said position. Furthermore, a sheave member 46 is arranged to guide the handle as well as to assist the operator by being provided with markings showing the hoisting, lowering and stop positions, and also the intermediate positions of hoisting at reduced speeds.

Mode of operation

In the drawing, Figure 1 illustrates the stop position, whereas Figure 2 depicts the hoisting position and Figure 3 the lowering position. In the stop position, the inlet 18, 19, 20 from the pump is connected to the pump suction line at 23 while the motor supply opening 25 is isolated from the motor discharge opening 26. In the hoisting position, the supply opening 25 is connected to the inlet 20 and the motor discharge opening 26 to the suction line 23. In the lowering position the opening 25 is connected to the suction line 23 and the opening 26 to the inlet 20.

In the position of Figure 2, representing full hoisting position, the slide member will be positioned at its lowermost position. In addition to the prior used arrangement of this control valve, such downwards movement of the slide member is limited by the upper end plate 34 engaging in this position with its lower face the upper end of the sleeve 39, said sleeve resting on the spring supporting disc 41, whereas said spring supporting disc 38 rests on the lower sleeve 41, which in turn rests on or is associated with the piston 32, whereby the downward movement of the slide member is limited to this extreme position.

In said extreme position the lower spring 37, which is received between the end plate 34 and the spring support 38, will be compressed; as is obvious the said spring will create a return force as soon as the operator releases the handle.

It may be advantageous, at the present stage of description, to consider the corresponding arrangement in the position of Figure 3, representing the position of full lowering, said position being the uppermost position possible of the slide member in the valve chamber.

Said upper end position is limited by the upper sleeve 35 engaging the lower face of the top cover 30 of the housing; simultaneously, the upper spring 36 will be compressed between said top cover and the plate 34. This will give a downwards directed return force.

However, the slide member has a substantial weight, which in addition to the spring force will act to force the slide member downwards. In order to counterbalance such weight of the slide member, the lower spring 37 is

given a pre-compression corresponding to said weight. In addition, both springs are given a small counteracting pre-compression in order to ensure correct return to the neutral position. It will be readily understood that the arrangement will give the desired return movement of the slide member, as soon as the operator releases the handle 17.

Although the entire valve chamber is filled with hydraulic fluid such as oil, the return movements aforesaid may nevertheless proceed at a dangerously high rate due to the high volume of fluid passing through the valve per unit of time in such valves for hydraulic winches of the stated kind. Furthermore, it is desirable to have relatively high return spring force in order to ensure safe return to the neutral position, which will necessarily give a high rate of return movement. This is dangerous, because the system will be subjected to abrupt changes in flow directions.

First of all, it should be obvious that movement 20 towards the position of hoisting will decrease the volume of the space within the slide member; said volume must in other words be increased again at the return movement to stop position. When moving the slide member towards the position of lowering, the said volume is increased and must be decreased when returning towards the stop position. During the first mentioned movement, hydraulic fluid must be sucked through the narrow passages 42 and 43, while during the second type of movement, the fluid must be pressed therethrough; consequently, an hydraulic dampening means will be enclosed in the hollow interior of the valve, such dampening means consisting in passing of hydraulic fluid to and from the interior space through narrow passages 42 and 43. For this reason, the return movement will proceed at a safely low rate.

However, when moving the valve member downwards, pressure fluid from the lower opening 20 will also flow from the supply conduit through the passage 42 of the intermediate flange 28, and will pass through the hollow interior of the slide member and through the passage 43 of the upper plate member 34; this flow will result in a slight increase of the pressure towards the slide member at its upper end when same is moved in a downward direction. As is well known in the art, such slide valves are normally counterbalanced as to pressure by having end flanges of equal diameters, both end flanges being subjected to the same pressure, that is, discharge pressure in the present embodiment. However, this counterbalance will be somewhat changed during the downward movement, due to the flow aforesaid.

The unbalance, although small, supports the downward movement of the slide member, making it easy to move same downwards. A remarkable feature is that the stated effect is more significant at higher pressures, that is, when higher loads are hoisted. At such higher pressures there will normally be a higher need for such assistance in the downward movement, as the high pressure of the fluid flowing from the supply openings 19 and 20 will tend to urge the slide member laterally towards the wall of the valve chamber, whereby the friction between the slide member and the wall is increased.

In the upward movement of the slide member towards the lowering position, such higher pressures will not be created in the system. Furthermore, when lowering higher loads, there will be a flow under high pressure from the opening 25 to the opening 24, which will create an upwards directed force to assist the movement towards the upper end position.

The flow conditions mentioned above will not materially affect the return movements explained previously.

While there is in this application specifically illustrated and described one form which the invention may assume in practice, it will of course be understood that the showing provided is for the purpose of illustration only and that the invention may be further modified and em-

bodied in various other forms without departing from its scope as defined by the appended claims.

What I claim is:

1. A manually operated control valve for hydraulic transmission systems, comprising a housing having a valve chamber, a supply conduit coupled to said housing and adapted for conveying pressure fluid from a fluid source to said valve chamber, a conduit coupled to said housing and adapted for conveying discharge fluid back to said fluid source from said valve chamber, conduits coupled to said housing and adapted for supplying and discharging hydraulic fluid to and from a hydraulic motor means from and to said valve chamber, all of said conduits opening into said valve chamber at spaced positions, a slide member displaceably mounted within said valve chamber, said slide member including flanges for dividing the valve chamber into communication spaces for setting up desired flow paths for the hydraulic fluid from one conduit to another within said valve chamber, a manually operable control handle, said control handle being connected to the slide member whereby movement of said control handle to and from a central position into one of two opposite directions will move the slide member so as to shift the flow paths of said valve chamber, said central position representing a stop position of said motor means whereas the movement into a respective one of said opposite directions is adapted to set up flow paths to drive the hydraulic motor means in a respective one of opposite directions, means for resiliently urging said control handle towards its central position, and means for dampening the return movement to said central position as a result of a manual displacement therefrom and subsequent release of said control handle, said valve further comprising two compression springs arranged to urge the slide member towards a stop position in counteracting arrangement, one of said compression springs being arranged to receive and counteract the weight of the slide member.

2. A manually operated control valve for hydraulic

systems, comprising a housing having a cylindrical valve chamber bore, a piston connected to said housing, conduits adapted for connection to and from a pressure fluid source leading into said bore at axially spaced positions therein, conduits adapted for connection to and from a hydraulic motor means and leading into said bore at other axially spaced positions therein, a slide member axially displaceable within said bore, said slide member carrying flanges for dividing said bore axially into a number of closed spaces for setting up communication paths between said conduits, manually operated means for axially displacing said slide member within said bore to shift the pattern of communication paths between said conduits, return means for said slide member, a cylindrical space within said slide member, said cylindrical space being closed at one end and receiving at its opposite end the piston connected to said housing, and a restricted passage for supplying hydraulic fluid to the space within the slide member, the axis of said bore extending substantially in a vertical direction, the return means for said slide member comprising compression springs arranged in counteracting arrangement to urge the valve member to a central position, one of the compression springs urging the valve member in an upward direction and having a force sufficient to counteract the weight of the slide member as well as the force from the other spring which acts downwardly.

3. A manually operated control valve according to claim 2, wherein a restricted flow of fluid is set up to assist in the manually operated movement of the control valve member in movements from the central position.
